UNITED STATES PATENT OFFICE.

JOHN A. BARNES, OF WEST NEW BRIGHTON, NEW YORK, ASSIGNEE TO THE SUPER-HEATER COMPANY, OF NEW YORK, N. Y., A CORPORATION OF DELAWARE.

BOILER WITH SUPERHEATER.

Application filed February 17, 1919. Serial No. 277,802.

To all whom it may concern:

Be it known that I, JOHN A. BARNES, a citizen of the United States, residing at West New Brighton, county of Richmond, State of New York, have invented certain new and useful Improvements in Boilers with Superheaters, of which the following is a specification.

This invention relates particularly to water tube boilers of the type having front and rear headers shaped like flat boxes and connected by water tubes, and provides a space for the superheater and convenient means of making the space accessible for inserting the superheater units or withdrawing them.

I am aware that constructions have been proposed heretofore for omitting some of the water tubes in boilers of this type and occupying the space thus provided by superheater tubes. These superheater tubes are usually located not directly above the fire, but so that one or more rows of water tubes intervene.

There arises at once the problem of satisfactory means of access to the space where the superheater is placed. Not only is it necessary to make inlet and outlet connections for the steam; but it is also highly desirable to make the connections of the individual superheater units to the headers accessible for inspection and repair. The superheater, it will be understood, is practically always made up of lengths of pipe connected to a header or headers. In some previously proposed superheater constructions for use in connection with boilers of the type I am speaking about, the ends of the pipes projected through thimbles connecting the two walls of the boiler header, and the superheater headers were located on the outside. This entails the difficult task of keeping tight the joints between the thimbles and boiler headers, and has the serious disadvantage of interfering with the circulation in the boiler. In fact, this latter difficulty puts the use of this construction entirely out of the question in some boilers.

The present invention resembles the constructions referred to in omitting some of the water tubes and replacing them by the superheater units. It also places the superheater headers outside of the boiler header, but it uses entirely novel means for permitting the ends of the superheater units to pro-

ject from the space where the units are located so they may joined to the headers.

The invention is illustrated in the two sheets of drawings filed herewith, in which Fig. 1 shows in longitudinal section a boiler with my invention applied the section being on line 1-1 of Fig. 2; Fig. 2 is a fragmentary sectional view on line 2-2 of Fig. 1; Fig. 3 is a front elevation of the same boiler, portions being shown as broken away; Fig. 4 is an enlarged detail front view; Figs. 5 and 6 are fragmentary front and longitudinal sectional view of a different form of boiler with my invention applied.

The boiler to which my invention is shown applied in Figs. 1 to 4, is, in general, one of an ordinary commercial type. Water tubes 1, inclined to the horizontal, connect front and rear headers 2 and 3, the front header 2 communicating on its upper end with the steam and water drum which is connected to the rear header 3 by means of a set of pipes 5. This structure is mounted above a furnace 6, the products of combustion from which are suitably baffled as they pass between the tubes 1, and leave for the stack through the connection 7.

In the proposed prior constructions spoken of above for accommodating superheater tubes in lieu of some of the water tubes, openings through either or both of the headers 2 and 3 were required for insertion or withdrawal of the superheater tubes. In the construction according to my invention, as illustrated in the drawings, the lower part of the front header 2 is provided with a series of passages or notches 8, extending upward from the lower end of the header, and separated from each other by extensions 9 of the header. Tubes connect the extensions 9 with the rear header, but there are of course no water tubes in the spaces behind the passages 8. These spaces are occupied by the tubes 10 of the superheater. In the case illustrated, each space is occupied by three superheater elements. The middle one of these, 10^a, consists of four connected pipe lengths vertically aligned; while each of the outer two elements comprises four vertically aligned lengths and two horizontally aligned lengths below them. The pipe lengths of each element are connected by return bends so as to make up a continuous conduit; and the two ends of each element are connected respectively to the two super-

heater headers 11^a and 11^b. Any suitable means for effecting this connection will answer, but preferably one admitting of ready, detachment and reattachment. The ends of the elements are seen to extend through the spaces 8. Surrounding them and filling up the spaces so as to prevent air from leaking in is the fire-clay or similar material 12. A casing 13, provided with a suitable door 14, encloses the front.

It may prove desirable in some cases to protect the superheater elements somewhat from too direct exposure to the heat from the furnace; and for this purpose the lowest row of water tubes 1^a is offset, as clearly shown in Figs. 2, 3, and 4, so as to lie under the elements for the greater part of their length.

Steam, either from the boiler in which the superheater is located, or from another source, is supplied to one of the headers 11^a and 11^b, circulates through the superheater elements 10 and is superheated, and is taken off from the other header and carried to the point of use.

It will be seen that if it is desired to remove a superheater element for any purpose, this removal is effected by merely removing the fire-clay 12, and detaching the element ends from headers 11^a and 11^b, whereupon the element can be withdrawn.

The same general idea for providing a readily accessible superheater space is applicable to boilers in which the front and rear headers are made up of a set of separate boxes such as illustrated in Figs. 5 and 6. Alternate of these boxes are made shorter, as at 8^a, and the superheater elements 10 have their ends projecting out through the space thus provided. The construction in other respects is very similar to that previously described and need not be elaborated on.

It will be evident that the details of the arrangement may be considerably varied without departing from the spirit of the invention. Thus the particular shape of the elements, the number of their loops, etc.,

need not be precisely as shown. The notches 8 may evidently be equally well made in the rear header; or if desired they may be made in both, and superheater headers be located at both ends.

These and similar variations will readily suggest themselves.

What I claim is:—

1. In a boiler, the combination of a header; a second header opposite the first, and shorter than it but having a series of spaced downward extensions making the overall length of the two headers substantially the same; water tubes connecting the second header and its extensions to the first header; and a superheater comprising tubular units located in the spaces between the water tubes connected to the extensions.

2. In a boiler, the combination of a header; a second header opposite the first and shorter than it but having a series of spaced downward extensions making the over-all length of the two headers the same; water tubes connecting the second header and its extensions to the first header, and a superheater comprising tubular units located in the spaces between the water tubes connected to the extensions, the ends of the units extending through the spaces between the extensions and connected to a superheater header.

3. In a boiler, the combination of a header; a second header opposite the first and shorter than it but having a series of spaced downward extensions making the overall length of the two headers the same; water tubes connecting the second header and its extensions to the first header; tubular superheater units located in the spaces between the water tubes connected to the extensions; and a superheater header adjacent to the second header on the side away from the water tubes and out of line with the superheater units, the ends of the units projecting through the spaces between the extensions and being bent toward and secured to the header.

JOHN A. BARNES.
